UNITED STATES PATENT OFFICE

158,618

CABINET FOR A TELEVISION RECEIVER

Peter Schladermundt, Bronxville, N. Y., and Charles L. Metzler, Palisades, N. J., assignors to Avco Manufacturing Corporation, Cincinnati, Ohio, a corporation of Delaware

Application April 26, 1949, Serial No. 2,273

Term of patent 3½ years

(Cl. D56—4)

To all whom it may concern:

Be it known that we, Peter Schladermundt, a citizen of the United States, residing at Bronxville, New York, in the county of Westchester, and Charles L. Metzler, a citizen of the United States, residing at Palisades, New Jersey, in the county of Warren, have invented a new, original, and ornamental Design for a Cabinet for a Television Receiver, of which the following is a specification, reference being had to the accompanying drawings, forming a part thereof.

In the drawings:

Fig. 1 is a perspective view of the front, right side and top panels of a cabinet for television receiver showing our new design;

Fig. 2 is a side elevational view thereof; and
Fig. 3 is a rear elevational view.

We claim:

The ornamental design for a cabinet for a television receiver, as shown.

PETER SCHLADERMUNDT.
CHARLES L. METZLER.
